Patented Apr. 20, 1920.

Inventor
E. V. GANDIL

BY: Frank Deem
ATTORNEY.

UNITED STATES PATENT OFFICE.

ERNST VALDEMAR GANDIL, OF COPENHAGEN, DENMARK.

DOOR-SPRING.

1,337,763.

Specification of Letters Patent. Patented Apr. 20, 1920.

Application filed July 10, 1918. Serial No. 244,219.

To all whom it may concern:

Be it known that I, ERNST VALDEMAR GANDIL, a subject of the King of Denmark, residing at Copenhagen, Denmark, have invented new and useful Improvements in 5 Door-Springs; and I do hereby declare the following to be a full, clear, and exact description of the same.

The invention relates to a door spring of 10 the kind in which a spring which is tightened during the opening of the door, closes the door while an oil-brake effects an even and checked closing movement. In the hitherto used door springs of this type the 15 said spring consists in a flat spiral spring which is rather expensive and easily broken. Further, to these known constructions is attached the drawback that it is difficult to obtain a sufficiently good tightening of the 20 spaces containing the oil.

The invention aims at avoiding these drawbacks and upon the whole to produce a durable, most effective and strong door spring, and this is obtained by arranging 25 inside the casing of the door spring two cylinders, one inside the other and mutually connected by means of a thread, one of the cylinders being turnable but indisplaceable in axial direction and actuated for turning 30 through opening of the door, while the other conveniently is displaceable but in axial direction and is under influence of a helical spring. When thus the former cylinder is turned in a certain direction, the 35 cylinders will screw themselves out of one another, whereby the cylinder actuated by a spring is displaced in axial direction in such a manner that the spring is tightened and thereby put into a position to effect the closing 40 of the door.

A modification of the invention is shown in the drawing, where—

Figure 1 shows a section through a door spring in front view.

Fig. 2 a side view of the same and

Fig. 3 a top view of the door spring shown in Figs. 1 and 2 at a smaller scale and with omission of certain details, arranged on a door.

The casing *a* of the door spring, which is 50 filled with oil, or nearly so, is integral with a plate *b*, whereby it can be fixed in a vertical position on the upper part of a door *E*, Fig. 3. The uppermost part of the casing *a* is bored out into a cylinder *c*, in which is

turnably arranged a cylinder *d* forming a

lid for the casing *a*. As shown in the drawing the sliding surface between the cylinders *c* and *d* is rather long so that in this place is obtained a good closure for the oil. 60 Inside the cylinder *d* according to the shown modification is arranged a second cylinder *e* which is guided in perpendicular direction by a guiding list or spring *f* extending from the lowermost end of the cylinder *e* sliding 65 in a groove *g* cut in the inner side of the casing *a*. This groove may in an amended modification be produced as a steep helical groove in such a manner that the cylinder *e* may be allowed to carry out a slight turning 70 movement during the opening and closing of the door.

A helical spring *h* abutting partly against the bottom of the cylinder *e* and partly against a normally stationary but adjustable 75 piston *i*, tends at pressing upward the said cylinder. A regulation of the tension of the spring can be obtained through turning of a square tap *D* on the end of the rod *j* of the piston *i*, the former, which is led 80 tightly through a lid *l*, passing with its helical part through the bent nut-shaped end of an arm *k* fastened on the lid *l*.

The cylinder *d* rests with a collar *m* on the uppermost edge of the cylinder *c* and is 85 prevented from moving upward by an arm *p* which is fixed on the casing *a* and forms a bearing for a tap *q* on the cylinder *d*, pressing a ball row *o* which is arranged in a ring-shaped groove *n* in the upward looking side of the bottom of the cylinder *d*. On 90 the tap *q* is removably fastened an arm *r* which by means of a link *F*, turnable in both ends and with adjustable length, in a known manner is connected with a mounting 95 *G*, fastened to the frame *H* above the door, *vide* Fig. 3.

In the side wall of the cylinder *d* is bored a vertical narrow channel *t* and in connection with the same a horizontal channel *u*, 100 the free passage area for the oil of which can be narrowed through a valve screw *v*. In the bottom of the cylinder *e* is a conical boring *z* which through a channel *w* is in connection with the inner cylinder and 105 which forms the seat for a ball *x* which by means of a tongue *y* not covering the entire opening *g* is in known manner prevented from leaving this opening or boring.

Thus the cylinders *d* and *e* are mutually 110 connected and one of these can, by a screwing action, be moved out of and into the

other. This action is, in the embodiment shown in the drawing, appropriately produced by helical grooves B and A formed in the cylinders *d* and *e*, respectively, and cut 5 opposite to one another, said grooves jointly forming a helical tube containing one or more balls C. As a result there is provided a very practical construction for the mounting and dismounting of the apparatus, and 10 the least possible loss by friction is sustained through the mutual movement of the cylinders *d* and *e*.

The cross section of the grooves A and B may be rectangular as shown or circular. 15 The apparatus acts in the following manner.

When the door E is opened in the direction of the arrow 1 in Fig. 3, the arm *r* is turned and therewith the cylinder *d* part 20 of a revolution in the direction indicated by the arrow 2, whereby the cylinder *e* owing to the screw connection A, B, C is pressed a distance downward so that the spring *h* is tightened. At the same time 25 part of the oil from the lowermost part of the casing *a* is driven through the channel *w* and the boring *z* into the space above the cylinder *e*, the ball *x* being lifted from its seat. When then the door is released, the 30 strongly tightened spring *h* will lift the cylinder *e* and thereby turn the cylinder *d* whereby the door is closed. As, however, the ball *x* will now assume its seat, the oil cannot get this way but is forced to stream 35 through the channel *u* and the long narrow channel *t* which takes a certain time so that the closing movement of the door is checked.

It will be seen that the special arrangement shown in the drawing of the cylinders 40 *d* and *e* and the spring *h* permits the casing *a* to be made comparatively short, as part of the spring *h* can be accommodated in the inner of the cylinder *e*.

In order to suffer the oil to stream from 45 one side to the other of the piston *i* when the same is adjusted for regulating the tension of the spring, holes *s* are bored through the said piston.

Having thus fully described my invention, 50 I claim as new and desire to secure by Letters Patent in U. S. A.

1. A doorspring comprising an outer casing adapted to be secured on a door and to contain a fluid, a hollow cylinder mounted 55 within the said casing and adapted to be connected with a door frame and rotated upon opening of the door, a second hollow cylinder constituting a piston and arranged to slide tightly in the cavity of the said first 60 named cylinder, means, including a screw thread, for causing an axial displacement of the said piston relatively to the said cylinder upon turning of the latter, a helical

spring acting upon the said piston, a valve member carried by said piston and a checked channel connecting a space above the said piston with a space below the same. 65

2. A doorspring comprising an outer casing adapted to be secured on a door and to contain a fluid, a hollow cylinder mounted within and also forming a lid for the said casing and adapted to be connected with a door frame and rotated upon opening of the door, a second hollow cylinder constituting a piston and arranged to slide tightly in the cavity of the said first named cylinder, means, including a screw thread, for causing an axial displacement of the said piston relatively to the said cylinder upon turning of the latter, a helical spring acting upon 70 the said piston, a valve member carried by said piston and a checked channel connecting a space above the said piston with a space below the same. 75

3. A doorspring comprising an outer casing adapted to be secured on a door and to contain a fluid, a hollow cylinder mounted within the said casing and adapted to be connected with a door frame and rotated upon opening of the door, a second hollow cylinder constituting a piston and arranged to slide tightly in the cavity of the said first named cylinder, means, including a screw thread, for causing an axial displacement of the said piston relatively to the said cylinder upon turning of the latter, a helical spring partly housed in the cavity of the said piston and acting upon the latter, said spring abutting against an adjustable stop arranged in the said outer casing, a valve member carried by said piston and a checked channel connecting a space above the said piston with a space below the same. 85 90 95

4. A doorspring comprising an outer casing adapted to be secured on a door and to contain a fluid, a hollow cylinder mounted within the said casing and adapted to be connected with a door frame and rotated upon opening of the door, a second hollow cylinder constituting a piston arranged to 105 slide tightly in the cavity of the said first named cylinder, means, including a screw thread, for causing an axial displacement of the said piston relatively to the said cylinder upon turning of the latter, a helical spring 110 acting upon the said piston, a valve member carried by said piston and a checked channel formed in the wall of the said rotatable cylinder and connecting a space above the said piston with a space below the same. 115 120

In testimony whereof I have affixed my signature in presence of two witnesses.
